RESISTOR CONSTRUCTION

John H. A. Kohler, Philadelphia, Pa., assignor to
 International Resistance Company, Philadelphia, Pa., a corporation of Delaware

Application July 27, 1940, Serial No. 347,848

3 Claims. (Cl. 201—67)

This invention relates to an electrical resistor construction and more particularly a hermetically sealed unit suitable for efficient operation under a variety of weather conditions.

One of the objects of this invention is to provide a resistor construction which will be mechanically and electrically durable and well able to withstand indefinitely the destructive effects of extremely adverse weather conditions. Another object is to provide a construction of the above character susceptible of economical manufacture from inexpensive materials. Another object is to provide a construction of the above character in which all electrical parts subject to damage from weather conditions are completely sealed therefrom by rugged and permanent structure. Other objects will be in part obvious and in part pointed out hereinafter.

The invention accordingly consists in the features of construction, combinations of elements and arrangements of parts as will be exemplified in the structure to be hereinafter described and the scope of the application of which will be indicated in the following claims.

In the accompanying drawing in which is shown one of the various possible embodiments of my invention:

Figure 1 is a perspective view of the complete resistance unit;

Figure 2 is a longitudinal sectional view of the unit shown in Figure 1;

Figure 3 is an enlarged fragmentary longitudinal sectional view of a portion of the structure shown in Figure 2; and

Figure 4 is a transverse sectional view taken along the line 4—4 of Figure 2.

Similar reference characters refer to similar parts throughout the several views of the drawing.

Certain problems and difficulties inherent in resistor units now in general use form a basis for a more ready comprehension of some of the important features of this invention. When resistance units and like equipment are used for maritime radio equipment or like purposes, the variety of weather conditions encountered in use is such as to produce rapid deterioration of any exposed parts resulting in breakdowns and general inefficient operation. Not only are such units exposed to every variety of temperature from the equator to the arctic regions but also the saline atmosphere encountered has a very damaging effect. For example, humidity and salt air may corrode the resistance wire and there may also be an anodic or electrolytic ac-

tion. Resistance wires are often made from alloys having as ingredients dissimilar metals and in the presence of salt water a voltage is set up between two points in the wire resulting in rapid deterioration thereof by the electrolytic action. Resistance units now used in an attempt to overcome this difficulty are generally characterized by chemical protective coatings of various types such as vitreous enamels, cements and the like. While the mechanical protection offered by these coatings delay to some extent the effects of humidity and salt air, eventual penetration is effected and, as a matter of fact, some of these coatings even contribute to the difficulty because they contain salts which combine with the water to produce the electrolytic action. Furthermore, these coatings are often vulnerable to temperature changes which effect breakdowns, thus creating openings for the penetration of the saline atmosphere. One of the objects of this invention is to provide a construction in which the above-mentioned difficulties as well as many others are successfully overcome.

25 Referring to Figure 1 of the drawing, there is shown a resistance unit enclosed in a casing 15 and having at each end terminals 11 and 12 preferably of annular shape for more ready connection in desired circuits. The resistance unit together with all parts thereof vulnerable to weather conditions are hermetically sealed within the casing 15 as will be more fully described hereinafter.

30 More particularly, as better shown in Figure 2, the unit consists of a core, which is preferably a ceramic tube 13, having wound thereon resistance wire 14. Tube 13 with the wire wound thereon is enclosed in a cylindrical casing 15 and terminals 11 and 12, preferably cup-shaped, fit 40 over the ends of tube 13 and are connected to the opposite ends of the wire 14. The opposite ends of casing 15 are sealed to terminals 11 and 12 so that the resistance wire is completely encased and hermetically sealed from the atmosphere by the terminals 11 and 12 and the casing 15.

45 Accordingly, the resistance wire and its connections with the terminals 11 and 12 are so protected in this enclosure that they cannot be effected by any atmospheric conditions and, more particularly, the action of salt and water which, as previously noted, is very harmful to these parts. Furthermore, the casing 15 and the terminals 11 and 12 may be made from durable materials well able to stand up under the variety of weather conditions which this unit is de-

signed to withstand. There are no openings or crevices through which the atmosphere might attack the vulnerable parts of the resistance unit and the only seams through which leakage might occur are constructed to withstand any breakage in a manner to be pointed out more fully hereinafter.

Tube 13 is preferably formed from a dielectric ceramic material, the principal characteristic of which should be its ability to withstand extreme temperature changes without breakdown. Terminals 11 and 12 have cup-shaped portions 11a and 12a fitting over the opposite ends of tube 13 and preferably cemented thereto. Cup-shaped portions 11a and 12a terminate in annular flanges 11b and 12b extending outwardly therefrom and merging into inwardly extending cylindrical portions 11c and 12c. Cylindrical portions 11c and 12c fit tightly within casing 15, thus to support the casing in spaced relation to the resistance wire 14 and provide the desired sealed space. Lips 11d and 12d preferably cut from cylindrical portions 11c and 12c are bent downwardly and the ends of wire 14 fit between the lips 11d and 12d and the cylindrical portions 11c and 12c preferably being silver soldered or otherwise electrically connected in this position, as shown in greater detail in Figures 3 and 4. Thus, terminals 11 and 12 are electrically connected to the resistance wire 14 at points within the sealed space so that harmful atmospheric conditions cannot attack these vulnerable parts of the resistance unit. The space for the wire 14 defined by the casing 15, the tube 13 and the terminals 11 and 12 is preferably tightly packed with an insulating medium, preferably an inorganic cement such as porcelain cement.

For the reasons mentioned above, it is most important to provide a durable hermetic seal between the terminals 11 and 12 and the casing 15. For this purpose I prefer to form the casing 15 from a glass and the terminals 11 and 12 from a metal so chosen that a bond may be effected therebetween. For example, the casing 15 may be formed from a glass known to the trade as "G705AJ," manufactured by the Corning Glass Company, and the metal, which must have the same coefficient of expansion as the glass, may be an iron-nickel-cobalt alloy such as that presently being sold in the trade as "Kovar." Other glasses and other metals might be used for the casing and the terminals respectively, the principal prerequisites for which are substantially equal coefficients of expansion and the creation of a bond therebetween by the application of heat. Glass-metal seals of the type utilized for this construction are disclosed in considerable detail in Patent No. 2,062,335.

After the unit has been assembled as described above, the opposite ends thereof are subjected to high temperatures, i. e. the melting temperature of the glass from which the casing 15 is formed, so that the edges of the casing melt and flow over the upper portions of the annular flanges 11b and 12b. The glass wets the oxidized metal surface with which it comes into contact, thereby forming a perfect bond therewith as it cools. Thus, upon cooling, the ends of casing 15 have formed thereon inwardly extending annular ridges 15a and 15b engaging and bonded to the flanges 11b and 12b (Figure 3). In practice, preparatory to this sealing operation, I have found it desirable to heat the terminals 11 and 12 at temperatures on the order of 1800° F. in

a hydrogen atmosphere to eliminate all traces of gas from the metal so that no bubbles or gas pockets will be formed during the sealing operation; such formations materially reduce the ability of the resultant seal to withstand stresses introduced by temperature changes. The metal ends are then rapidly oxidized so as to give an oxidized surface for the glass to wet. The resultant bond between the casing 15 and the terminals 11 and 12 provides a perfect hermetic seal for the interior parts of the resistance unit and, more particularly, the resistance wire 14 with its connections to the terminals.

The outer structure, i. e. the terminals 11 and 15 12 and the casing 15 of the resultant resistance unit are thus formed from materials well able to withstand any weather conditions without deterioration. Of course, the metal chosen for the terminals 11 and 12 is not only selected for its ability to form the above-described bond with the glass casing 15, but also for its ability to withstand the corrosive effect of weather conditions. In practice, the seal between the casing 15 and the terminals 11 and 12 has been found to be durable, to maintain a hermetic seal and thus prevent any seepage of atmosphere, water or chemicals to the interior of the unit where they might damage the wire 14 and connected parts. Not only is this resistance unit designed to stand up under most extreme atmospheric conditions 30 but also it has a marked ability to remain unaffected by sudden temperature changes over wide ranges.

It will thus be seen that I have provided a 35 thoroughly practical and efficient resistance unit in which the several objects hereinabove referred to as well as many others are successfully and efficiently accomplished.

As many possible embodiments may be made of 40 the above invention and as many changes might be made in the embodiment above set forth, it is to be understood that all matter hereinbefore set forth, or shown in the accompanying drawing, is to be interpreted as illustrative and not in 45 a limiting sense.

I claim:

1. In resistor construction, in combination, a glass tube member, a dielectric core, a resistance element wound on said core, said core being positioned within said tube member and having its ends extending from the ends thereof, and metal cap members fitting over and being mounted on each end of said core and covering the ends of said tube member, there being a glass-to-metal seal between said cap members and said tube, said cap members and tube members having the same coefficients of expansion and hermetically sealing said resistance element from the atmosphere.

2. In resistor construction, in combination, a glass tube member, a ceramic core, a resistance element mounted on said core, said core being positioned within said tube member and having its ends extending from the ends thereof, metal cap members fitting over and being mounted on each end of said core, and having annular flanges extending outwardly from the open ends thereof, the peripheries of said flanges being connected to and completely covering the open ends of said tube member by a glass-to-metal seal, said tube and cap members having the same coefficients of expansion and hermetically sealing said resistance element from the atmosphere, and means electrically connecting the ends of said resistance element to said cap members.

3. In resistor construction, in combination, a glass tube member, a resistance element mounted within said tube member, metal cap members having annular flange portions extending outwardly from the open ends thereof and thence inwardly, said flange portions being L-shaped in cross section, said flange portions fitting within the ends of said tube member and being con-

5 nected thereto by a glass-to-metal seal to completely cover and seal said ends from the atmosphere, said tube and cap members having the same coefficients of expansion, and means forming electrical connections between said resistance element and said flange portions.

JOHN H. A. KOHLER.
